CLAIM

The ornamental design for a projector lamp, as shown and described.

DESCRIPTION

FIG. 1 is a front, bottom perspective view of a projector lamp design showing my new design.

FIG. 2 is a front view of a projector lamp.

FIG. 3 is a rear view of a projector lamp.

FIG. 4 is a left side view of a projector lamp.

FIG. 5 is a right side view of a projector lamp.

FIG. 6 is a top view of a projector lamp.

FIG. 7 is a bottom view of a projector lamp.

FIG. 8 is a rear, top perspective view of a projector lamp; and,

FIG. 9 is a front perspective view thereof, showing the projector lamp separated into two components for clarity of disclosure.

The broken lines in the drawings depict portions of the projector lamp that form no part of the claimed design.
